UNITED STATES PATENT OFFICE

PETER RUTTEN, OF OSAKIS, MINNESOTA

PORTABLE SILO OR THE LIKE

Application filed May 25, 1931. Serial No. 539,812.

This invention relates to portable building structure especially adapted for silos, cribs, bins, brooders and other buildings of cylindrical shape.

5 It is an object of my invention to provide a simple, extremely economical and highly efficient portable silo or building structure adapted to be quickly and easily set up or dismantled and capable of being rolled up 10 into compact form for storage or shipment.

It is a further object to provide a silo or building structure of the class described which is very strong and durable when set up and in which provision is made for contraction and expansion of the material from 15 which constructed.

More specifically it is an object to provide a silo or building structure composed of a series of flexible sections each comprising a multiplicity of staves or slats and reinforced and connected for flexing by suitable encircling elements to form a strong reinforced substantially rigid structure.

20 Another object is to provide a silo structure of the class described wherein provision is made for silo doors and a sectional chute and wherein the structure including the door sections and doors are reinforced 25 and operatively held by means of adjustable encircling elements provided with tensioning means such as draw bolts or turn buckles.

These and other objects and advantages of 30 the invention will be more fully set forth in the following description made in connection with the accompanying drawings, in which like reference characters refer to similar parts throughout the several views, 35 and in which:

Fig. 1 is a front elevation of a three-section silo embodying my invention;

Fig. 2 is a top plan view of the same;

Fig. 3 is a perspective view showing one 40 of the silo sections dismantled and rolled up into a compact cylindrical bundle;

Fig. 4 is a fragmentary front elevation showing the draw bolt or tensioning means for securing the ends of the encircling 45 wires;

Fig. 5 is a fragmentary plan view showing the upper ends and joints between the slats or staves;

Fig. 6 is a fragmentary vertical section showing the manner in which two of the 55 silo sections are secured together at their abutting edges;

Fig. 7 is a fragmentary vertical section showing the lapping means or band for securing abutting chute sections together;

Fig. 8 is a front elevation of a suitable type of door section and frame including one of the doors, and

Fig. 9 is a vertical section taken on the line 9—9 of Fig. 8.

In the drawings an embodiment of my invention in the form of a silo is illustrated, although it will of course be apparent that my construction is also applicable to other cylindrical buildings, such as corn cribs, 70 bins and brooders.

The silo illustrated is not provided with a roof, but it will of course be understood that any suitable roof may be utilized if so desired, attached to the edges of the upper 75 silo section.

My structure as illustrated comprises several main silo sections indicated as entireties by the letters S and secured together in vertical end-to-end relation, and reinforced and held substantially rigid by means of encircling wires or rods 10. Each of said sections S comprises an elongated flexible strip constructed somewhat in the manner of flexible snow fencing material and comprising a multiplicity of parallel staves or slats 11, each secured by means of staples 12 (see Fig. 4) or other suitable attachment means to the encircling wires 10. Preferably three encircling wires are utilized for each section and as shown these wires are crimped or tortuously formed to allow for expansion and contraction of the slats due to weather conditions. The abutting longitudinal edges of the slats 11 are provided with complementary or matched joints permissive of flexibility between the slats. Various joint constructions may be used but I prefer the form illustrated in Fig. 5 wherein one edge of each slat is 100

provided with a longitudinal tendon 11a having a rounded projecting edge and wherein the opposite edge of said slat is provided with a mortise or groove having 5 a relatively wide converging V-shaped entrance portion 11b and a substantially parallel inner channel 11c adapted to loosely fit the projecting edge of the tendon 11a of the adjacent slat. The joints of the staves 10 or slats 11 are held in place by means of the staples or other attachment means engaging encircling wires 10.

For each of the flexible silo sections S a narrow and preferably rigid door section 15 DS is provided as shown comprising vertical slats 13 (see Figs. 1, 8 and 9) rigidly secured together by cross slats 14 and having a rectangular door opening in the medial portion thereof, which is closed by means 20 of a detachable door D. A door frame surrounds the door opening and is secured to the external side of door section DS, comprising the medially disposed cross slats 14 and short vertical slats 15 overhanging the 25 edges of the door opening to cooperate with the overhanging portions of medial slats 14 to form a flange or lip preventing outward displacement of the door. The door itself as shown is formed from a series of horizontal slats secured together by short cross slats 16. A horizontal rung or step 17 is rigidly connected to door D and cross slats 16 by suitable means such as bolts 17a and the same bolts may secure fastening arms 30 or turn cleats 18 which are adapted to be turned outwardly engaging the exterior of the short vertical slats 15 of the door frame to retain the door against inward displacement. The top cross slat 14 of each door 35 section is preferably provided with a U-shaped ladder rung or step 17 vertically aligned with the first mentioned step secured to the door.

The longitudinal edges of door sections 40 DS are matched with the edges of the silo sections S and in setting up the section, the flexible strip made up of staves 11 is arranged vertically and annularly and the ends thereof joined with the longitudinal edges of its door section DS as is clearly 45 shown in Figs. 2 and 4. The encircling wires 10 have adjustably connectable free ends, one of which, as shown, carries a draw bolt 10a and the other of which carries an L-shaped attachment strap 10b having a bolt-receiving aperture in the bent outer end thereof. The free ends and adjustable attachment means above specified are of 50 adequate length to extend across door section DS as shown in Fig. 4 and the entire silo section may be rigidly clamped together in cylindrical form by tightening the nuts of the draw bolts.

Each of the silo sections S carries at its 55 upper edge a series of circumferentially

spaced projecting saddles or attachment clips 19 which are adapted to embrace and secure the lower edge of the next annular upper section and which are bolted or otherwise secured to the lower section by means of suitable nutted bolts 19a. Between the abutting edges of two silo sections I prefer to interpose a packing strip 20 which may be constructed of felt or other suitable compressible material.

I provide efficient chute sections C for the upper silo sections, preferably constructed from similar slatted and flexible material and reinforced and held in bowed or U-shaped position by suitable encircling means, such as the wire cables 21. L-shaped attachment brackets 22 are secured to the longitudinal edges of chute sections C and preferably to the inner surfaces thereof and may be rigidly bolted to the door sections DS adjacent the longitudinal edges thereof. Each of the chute sections C is provided at its upper edge with an upstanding lip or band 23 adapted to lap beneath the lower edge of another chute section disposed thereabove, reinforcing the general structure and efficiently securing the chute sections together upon the exterior of the silo. The ends of wire cables 21 are made fast to the end slats of the chute section, and the other slats are each connected with the cable for flexing by suitable means such as staples.

My portable building structure may be very quickly and easily erected in the manner described by first rigidly coupling the body or silo sections with the cooperating door sections DS and adequately tightening the draw bolts associated with the encircling wires. The several then rigid sections may be superimposed upon the other in the manner shown in Fig. 1, the lower edges of the successive upper sections being received in the projecting saddles or clips 19 and efficiently anchored and secured thereby, the weight of said upper sections being transmitted directly upon the upper edges of the lower sections.

The chute sections C may then be successively attached to the structure by means of the angle attachment brackets 22. The first chute section is usually mounted at some distance above the ground line, as for example, upon the third section as shown in Fig. 1.

It will be seen that the cooperation of the encircling members or wires 12 with the matched or joined staves 11 provides a very strong, substantially rigid structure, the joints of which are secured by the engagement of the tendon portions 11a with the inner channels 11c of the complementary grooves. No lining is therefore required in my silo to prevent seepage of liquids through the walls.

The device may be very quickly dismantled by detaching the draw bolts 10a, loosen-

ing the encircling wires 10 and removing the several chute sections C and door sections DS. The main sections S may be quickly rolled into a compact cylindrical bundle for storage or shipment, as shown in Fig. 3, and the bundle may be bound in compact position by means of the encircling members 12. The chute sections C may also be rolled up into a compact cylindrical bundle after the cables or bands 21 are detached and the L-shaped attachment brackets 22 may be left on the chute sections and compactly rolled therewith or if desired, may be detached. The entire structure, including the rectangular flat door sections DS therefore requires very little space for storage or shipment.

From the foregoing description it will be seen that a very strong, durable portable building structure has been provided adapted to be manufactured at extremely low cost. The staves or slats of the sections can be cheaply prepared by milling machinery and are flexibly connected together by means of the staples or other attachment elements and the wire encircling members. The crimped or tortuous construction of the encircling wires adds a resiliency to the cylindrical sections which permits expansion or swelling of the individual staves due to weather conditions and which also permits some small amount of spaced relation between the longitudinal edges of the staves.

It will, of course, be understood that various changes may be made in the form, details, proportions and arrangement of the parts without departing from the scope of my invention, which, generally stated, consists in a device capable of carrying out the objects above set forth, and in the novel parts and combinations of parts disclosed and defined in the appended claims.

What is claimed is:—

1. In portable building structure of the class described, a plurality of substantially cylindrical sections each comprising a multiplicity of vertical staves and flexible encircling members to which said staves are attached, and means associated with at least one of the annular edges of each section for securing the adjacent section thereto with edges of said sections in abutment said sections forming a continuous wall and said sections being capable of being rolled into compact cylindrical form.

2. In portable building structure of the class described, a plurality of flexible strip sections each comprising a multiplicity of flexibly jointed vertical staves, encircling members for each section to which said staves are attached and which are adapted to hold said sections in substantially cylindrical form, and means for securing said sections together one above the other, said

strip sections being capable of being compactly rolled into cylindrical form.

3. In portable building structure of the class described, a plurality of substantially cylindrical sections each comprising a flexible strip made up of a multiplicity of flexibly jointed vertical staves and a plurality of encircling members to which said staves are attached and a relatively narrow rectangular rigid panel for each of said sections with which the ends of said flexible strip are joined, said encircling members having loose ends, and means associated with said ends for tensioning said encircling members.

4. In portable building structure of the class described, a plurality of cylindrical sections each comprising a multiplicity of flexibly jointed vertical staves and encircling members to which said staves are attached, the sections of said structure being superimposed one upon the other with their edges in abutment and a series of circumferentially arranged vertically projecting attachment saddles secured to one of the annular edges of each section for embracing and securing the abutting edge of the next successive section.

In testimony whereof I affix my signature.

PETER RUTTEN.
